UNITED STATES PATENT OFFICE

JOHN E. MILLETT, OF GARDNER, MASSACHUSETTS, ASSIGNOR TO AMERICAN FIBRE CORPORATION, OF GARDNER, MASSACHUSETTS, A CORPORATION OF MASSACHUSETTS

TWISTING MACHINE

Application filed May 6, 1927. Serial No. 189,225.

This invention relates to machines for forming up strand material from flat paper strips or the like. It is more particularly concerned with that portion of the mechanism by which the strip material is treated with glue or the like and then led to the strand-forming and twisting devices and more particularly to a machine having a considerable number of such devices each running substantially continuously.

One of the objects of this invention is to provide a glue circulating system which will insure a constant supply of glue properly conditioned for use to all the strips. For this purpose I provide an elevated tank for the glue from which it flows by gravity to preferably a pair of downwardly inclined troughs to each of which paper strips are passed on their way to the twisting mechanisms. From the lower ends of the treating troughs the glue flows through pipes to a pair of lower drain troughs inclined in the opposite direction from the lower ends of which the glue flows into a heated supply tank. The glue is pumped from the supply tank to the elevated tank. By the use of the elevated tank feeding by gravity to the upper treating troughs, the flow to these troughs may be regulated as desired independently of the pump which takes the glue from the supply tank so long as the pump is adequate to meet maximum requirements, any excess of glue supplied by the pump to the elevated tank being automatically returned therefrom through an overflow pipe to the supply tank, thus to govern the permissive height of glue in the elevated tank. The elevated tank acts also as an emergency supply which permits continued operation of the machine for a time after the stopping of the pump which may from time to time be necessary at least for short periods. Preferably the elevated as well as the lower tank are provided with heat insulating walls and when this is done it is usually unnecessary to provide heating means for the upper tank, though in order to maintain the glue in the proper condition it is usually desirable to supply heat to the supply tank. Drains are provided beneath the dies through which the strips pass and where they

are formed into strands, the glue squeezed from the strips by the dies being caught and flowing through the drains into the lower troughs which conduct it to the supply tank. The strips of paper in roll form are positioned above the treating troughs where there is ample room for large rolls.

A further feature of the invention relates to a device for guiding each strip of paper beneath the surface of the glue in the treating trough.

For a more complete understanding of this invention, reference may be had to the accompanying drawings in which

Figure 1 is a side elevation of a twisting machine embodying the invention.

Figure 2 is an end elevation thereof.

Figure 3 is a detail section to an enlarged scale on line 3—3 of Figure 1.

Figure 4 shows in perspective a drive for guiding a strip of paper through the treating trough.

Figure 5 is a detail section on line 5—5 of Figure 4.

Referring to these drawings, at 1 are indicated standards which may be made of pipe, supporting in a lower position a suitably jacketed supply tank 2 and thereabove an elevated tank 3. These tanks are positioned at one end of a twisting mechanism carried by frame members. The end frame members 5 are connected longitudinally at suitable intervals as by means of the horizontal beams 6 and 7 and support on each side an upper treating trough 10 inclined downwardly away from the tanks 2 and 3 and a lower drain trough 11 inclined in the opposite direction. The glue with which the strips are to be treated is pumped from the tank 2 through suitable piping 12 by means of the pump 14 to the elevated tank 3. From this tank extends an overflow pipe 15 which leads to the supply tank thus to maintain the proper height of glue in the tank 3. From one side of the tank 3 extends an outlet pipe 16 with which communicates a downwardly inclined pipe 17 provided with a T 18 at its lower end. From one side of this T extends a pipe 19 having a valve 20 therein, to the opposite side of the twisting machine where

it communicates through a downwardly inclined pipe 21 with the right hand trough 10 as viewed in Figure 2. From the other side of this T extends a downwardly inclined pipe 22 having a valve 23 therein, this pipe emptying into the adjacent end of the left hand treating trough as shown in Figure 2. At the opposite end of each of the treating troughs a pipe 24 conducts the glue to the higher end of the drain trough 11 on the same side of the frame and from the lower end of each of these drain troughs extends a pipe 25 which conducts glue back to the tank 2. The tank 2 may be provided with any suitable form of heating mechanism, a pair of leads 26 being shown extending to an electric heating unit within the tank.

Positioned along the top of the twisting frame are a series of supports 30 on which are rotatably carried rolls of paper 31, these rolls comprising strips of the proper width to be formed up into the strand material, there being shown a pair of series of these rolls, one series being positioned above each treating trough 10. From each of these rolls the paper extends beneath a bar 32 (see Figure 3) and thence to a device 35 which directs the paper strip beneath the level of glue in the treating trough. From this device each paper strip passes downwardly about a mandrel 36 suspended from a frame member 6, this mandrel projecting toward a strand forming die 38 positioned in the lower end of a cup shaped member 39. After passing through the die 38, the strip then being reduced to strand form, is conducted to a vertically arranged twisting mechanism of any suitable description such as indicated at 40 by which the strand is twisted into the desired form. From the cup shaped member 39 is a drain extension 45 leading to the adjacent drain trough 11. The heated glue is thus pumped from the supply tank to the elevated tank and from the elevated tank it flows by gravity to the upper end of the upper treating trough. As it flows down in this trough it acts upon the strips of paper which are passed therethrough, the glue that is not taken by the paper strips passing downwardly along the treating trough and from its lower end to the upper end of the draining trough from which it is conducted back to the supply tank. The glue being taken up by the paper strips is carried over therewith and a considerable portion thereof is squeezed out as the paper passes through the dies. The glue so squeezed out is conducted by the drain members 45 to the drain trough where it unites with the glue therein and is conducted back to the supply tank 2.

Should it be necessary for any reason to stop the operation of the pump, this may be done without interrupting the supply of glue to the upper treating trough until the level of the glue therein becomes too low to flow

out by gravity into the treating trough. Thus ordinarily ample time is given to make such minor repairs as may be necessary from time to time on the pump without necessitating the shutting down of the apparatus. Such shutting down is troublesome as the glue soon hardens and clogs the mechanism when it is not kept in circulation. 70

The device for causing the paper strips to pass through the glue in the treating troughs is preferably formed as shown in detail in Figures 4 and 5. Referring to these figures, 50 indicates a pair of spaced supporting bars joined at one end by a plate 51 which may, if desired, be fixed to one of the supports 30. At 80 their other ends the bars 50 are joined by a rod 52 over which the paper passes on its way to the mandrel 36. Positioned between the supporting bars 50 is a frame comprising a pair of side bars 55 and 56 joined at one end by a rod 57, which in the operation of the device is submerged in the glue in the treating trough. One of these frame members, as 55, is provided with an extension 58 in which is positioned a stop pin 59 which may rest on the upper face of its adjacent supporting bar to limit the extent to which the rod 57 may be moved downwardly from the supporting bars. 90

As shown best in Figure 5, one of the bars 55 or 56, herein shown as 56, has integral therewith at its end opposite to the rod 57 and parallel thereto a sleeve 60 one end of which bears against the bar 55. Passing through this sleeve is a screw 61 having its threaded extremity 62 in threaded engagement in an opening in the adjacent supporting bar 50. The head of the screw at 63 is seated in an opening in the opposite supporting bar 50. By tightening up this screw the sleeve 60 100 may be moved axially to press the frame side bar 55 into frictional engagement with the adjacent supporting bar 50, the frame bar 55 having an opening therein of sufficient size to receive the screw 61, but smaller than the sleeve 60 so that the end of this sleeve bears 110 thereagainst. By tightening the screw in this manner the frame may be held with the bar 57 in its lowered position so that the strip of paper is constrained to move downwardly 120 beneath the surface of the glue in the treating trough. After passing around the rod 57 beneath the surface of the glue it passes over the rod 52 at the outer ends of the supporting bar 50 and then passes down about the mandrel 36. 130

Having thus described an embodiment of this invention it should be evident to those skilled in the art that various modifications and changes might be made therein without departing from its spirit or scope as defined by the appended claims. 125

I claim:

1. In a machine of the class described, a supply tank, an elevated tank, means for

5 pumping liquid from said supply tank to said elevated tank, an overflow from said elevated tank to said supply tank, a downwardly inclined trough, means for conducting liquid by gravity from said elevated tank to the upper end of said trough, means for passing strips through the liquid in said trough, and means for conducting liquid from the lower end of said trough to said

10 supply tank.

10 2. In a machine of the class described, a supply tank, an elevated tank, a trough positioned below the said elevated tank and inclined downwardly away therefrom, means for pumping liquid from said supply tank to said elevated tank, an overflow from said elevated tank leading to said supply tank, valved means for conducting liquid from said elevated tank by gravity to the upper end of said trough, a series of vertical strand-forming and twisting mechanisms arranged below said trough, supports for holding a plurality of rolls of paper above said trough, means for conducting a strip of paper from each roll beneath the surface of liquid in said trough and from thence to and through one of said mechanisms, and means for conducting liquid from the lower end of said trough and that draining from said mechanisms to said supply tank.

15 3. In a machine of the class described, a supply tank, an elevated tank positioned above said supply tank, means for pumping liquid from said supply tank to said elevated tank, an overflow from said elevated tank to said supply tank, an upper trough positioned below said elevated tank and downwardly inclined therefrom, a lower trough below said upper trough and downwardly inclined toward said supply tank, valved means for conducting liquid from said elevated tank by gravity to the high end of said upper trough, means for conducting liquid from the lower end of said upper trough to the upper end of said lower trough, a series of vertically arranged dies positioned between said upper and lower troughs, means for supporting rolls of paper above said upper trough, means for conducting strips from said rolls beneath liquid in said upper trough and then downwardly through said dies, means for conducting liquid draining from said strips at said dies to said lower trough, and means for conducting liquid from the lower end of said lower trough to said supply tank.

20 4. In combination, a frame comprising side pieces, a rod joining said side pieces adjacent to one end, a sleeve arranged parallel to said rod and fixed to one of said side pieces adjacent to its other end and abutting against said other side piece, a pair of spaced supporting bars, and a screw passing through said side pieces and said sleeve, said screw having threaded engagement with one of said

supporting bars adjacent to said other side bar and having its head extending into an opening in the other of said supports when in tightened condition.

25 In testimony whereof I have affixed my ⁷⁰ signature.

JOHN E. MILLETT.
